(57) CLAIM

The ornamental design for a toilet brushware base, as shown and described.

DESCRIPTION

FIG. 1 is top view showing the new design.

FIG. 2 is a bottom view thereof.

FIG. 3 is a front view thereof.

FIG. 4 is a back view thereof.

FIG. 5 is a right side view thereof, the left side view being a mirror image of FIG. 5.

FIG. 6 is cross-sectional elevation view thereof taken along the line 6—6 in FIG. 1; and,

FIG. 7 is a perspective front, top and right side view thereof.

The broken lines in FIGS. 3 and 7 show a toilet brushware which stands in the base and forms no part of the claimed design.
